United States Patent Office.

JOHN P. PEARS, OF PITTSBURG, PENNSYLVANIA.

Design No. 4,640, dated February 7, 1871.

DESIGN FOR MOLDS FOR LAGER-BEER GLASSES.

The Schedule referred to in these Letters Patent and making part of the same.

To all whom it may concern:

Be it known that I, JOHN P. PEARS, of the city of Pittsburgh, in the county of Allegheny and State of Pennsylvania, have invented a new and useful Design for Mold for Lager-beer Glass; and I do hereby declare the following to be a full, clear, and exact description thereof, reference being had to the accompanying drawing making a part of this specification, which represents a sectional view of a glass-mold for pressing the bowls of ale or beer-glasses, my improved design being represented thereon.

To enable others skilled in the art to make and use my improved design, I will proceed to describe the same.

The mold cavity *a* is made in any of the ways known to the art in a two-part mold.

In that part of the cavity which forms the foot of the tumbler or glass, a groove, *b*, is made, which ex-

tends around the cavity in a plane at right angles to its axis.

Just above the bead *b* and extending around the cavity is a row or series of oval-shaped convexes, *c*, and above that about half way up the cavity, more or less, is another like row or series of convexes *c'*, each of which series of convexes makes a like series of concaves in the face of the tumbler.

What I claim as my improved design, and desire to secure by Letters Patent, is—

In the glass-mold cavity *a*, the groove *b* and convexes *c c'*, substantially as described and shown.

In testimony whereof I, the said JOHN P. PEARS, have hereunto set my hand.

JOHN P. PEARS.
